UNITED STATES PATENT OFFICE.

SIDNEY V. JAMES, OF NIAGARA FALLS, NEW YORK, ASSIGNOR TO THE SIMEON L. AND GEORGE H. ROGERS COMPANY, A CORPORATION OF CONNECTICUT.

DESIGN FOR A SPOON OR SIMILAR ARTICLE.

Application filed November 23, 1922. Serial No. 4,371. Term of patent 14 years.

To all whom it may concern:

Be it known that I, SIDNEY V. JAMES, a citizen of the United States, residing at Niagara Falls, in the county of Niagara and State of New York, have invented a new, original, and ornamental Design for a Spoon or Similar Article, of which the following is a specification, reference being had to the accompanying drawing, forming part thereof.

In the drawings, Figs. 1 and 2 show oppo-

site face views of the handle for spoon, or similar article, and Fig. 3 is a transverse section on an enlarged scale, on the line 3—3 of Fig. 1.

I claim:

The ornamental design for a spoon or similar article as shown.

SIDNEY V. JAMES.
